UNITED STATES PATENT OFFICE.

PAUL MOHRMANN, OF CHICAGO, ILLINOIS, ASSIGNOR TO FRIEDELEY VOSHARDT CO.,
OF CHICAGO, ILLINOIS, A CORPORATION OF ILLINOIS.

DESIGN FOR A LIGHTING FIXTURE.

Application filed September 29, 1922. Serial No. 3,840. Term of patent 7 years.

To all whom it may concern:

Be it known that I, PAUL MOHRMANN, a citizen of the United States, residing at Chicago, in the county of Cook and State of Illinois, have invented a new, original, and ornamental Design for a Lighting Fixture, of which the following is a specification, reference being had to the accompanying drawing, forming a part thereof.

Fig. 1 is a side elevation of a lighting fixture, showing my new design.

Fig. 2 is a semi-sectional view of the top of the lighting fixture.

Fig. 3 is a semi-sectional view of the bottom of the lighting fixture.

I claim:

The ornamental design for a lighting fixture, as shown.

PAUL MOHRMANN.
